UNITED STATES PATENT OFFICE.

FRANK M. LEAVITT, OF BROOKLYN, NEW YORK, ASSIGNOR TO THE VULCAN COMPANY, OF PHILADELPHIA, PENNSYLVANIA.

CORNICE-MACHINE.

SPECIFICATION forming part of Letters Patent No. 395,154, dated December 25, 1888.

Application filed December 14, 1887. Serial No. 257,848. (No model.)

To all whom it may concern:

Be it known that I, FRANK M. LEAVITT, a citizen of the United States, residing at Brooklyn, Kings county, New York, have invented 5 certain new and useful Improvements in Cornice - Machines, fully described and represented in the following specification and the accompanying drawings, forming a part of the same.

10 The object of this invention is to furnish novel means for adjusting in a machine such as described the pressing-tools toward one another. It is more especially intended for machines having long cross-heads in which are 15 employed two cranks and connecting-rods for transmitting equable motion to both ends of such cross-heads for bending sheet-metal cornices, &c. In such machines the connecting-rods are divided in the center and connected 20 together by expansion-nuts engaging right and left hand screw-threads upon the connecting - rods to shorten and lengthen the same; and this invention consists in the novel means hereinafter shown and described, and 25 then specifically pointed out in the claims, for accomplishing this result.

In the drawings, Figure 1 represents a front elevation of an eight-foot cornice-press provided with my improvements. Fig. 2 is a 30 rear elevation, partly in section where hatched, of the same. Fig. 3 is an end elevation of the same with the tightener shown in one position in full lines and in another position in dotted lines. Fig. 4 is a section of the bed, cross-head, and tools upon a larger scale, on line $x x$ in Fig. 1. Fig. 5 is a side view of the die-holder and die upon the same scale as in Fig. 4, and broken in the middle for want of room to show its entire length. Fig. 6 is a 35 plan of one of the keys for the die-holder upon a larger scale than Fig. 5. Fig. 7 is a plan of the nut-beam twice the size of that shown in Fig. 1. Fig. 8 is a view of the same from the side opposite to that shown in Fig. 2. Fig. 9 is a side view of one expansion-nut and its worm-wheel detached from the screws and of the same scale as Figs. 7 and 8; and Fig. 10 is a view of one of the connecting-rods complete, with the expansion-nut shown 45 in section, twice the size of that shown in Fig. 9.

The cornice-press shown herein is represented with vertical end frames, A A', tied together by a bed, B, and tie-rod B', and having a cross-head, C, suitably fitted between the same to slide up and down over the bed B. As shown in Fig. 4, the bed is provided with a grooved die, d, and the cross-head with a die-holder, d', carrying a die, e. The die-holder and die are shown in side view at Fig. 5, the die-holder being provided with two shanks, f, which are fitted to sockets in bosses s upon the cross-head, and held therein by keys g', one of which is shown in Fig. 6, fitted to notches g² in the edges of the shanks. 65 The cross - head is provided with slots g, adapted to receive the key at such point as it enters the notches g² in the shanks. The die e is secured in a continuous groove in the lower side of the holder d', and pins e' are 70 inserted through the holder and die to retain them together.

It has been common heretofore in such cornice-presses to form each die with shanks, as f, to fit sockets in the cross-head. In the machine as I construct it I employ a holder having upon one edge shanks as a means of attachment to the cross-head, and upon the opposite edge a groove to receive the smaller dies, which may be required at certain times 80 to be used in a large press.

By my construction the die may be made of a mere strip of flat wrought-iron adapted to fit the groove in the lower side of the die-holder, and may be cheaply secured therein 85 by drilling holes to fit the pins e'.

The key g' is shown with a ring, h, to pull it out when required, and the pins e' may be similarly constructed, if desired.

The motive power for the cross-head is represented in the drawings as a clutch-pulley, D, actuated by a lever, D', and treadle-rod D². The pulley is mounted upon a shaft, i, provided at one end with a pinion, j, to actuate a gear, k, upon the end of the crank-shaft k'. 90 Such shaft is provided with a bent crank (or an equivalent eccentric) near each end, and is connected with the cross-head by right and left hand screws l l', pivoted, respectively, to the cranks and top pivots m upon the cross-head. 95 The screws are connected by an expansion-nut, n, and are each provided with a worm-

wheel, n' , for rotating them simultaneously, and with jam-nut n^3 .

A nut-beam, o , is provided with a bearing, o^2 , at each end to fit the exterior of each nut n adjacent to the worm-wheel n' , and a worm-shaft, p , is mounted upon such beam in bearings o' adjacent to the worm-wheel, between which bearings a worm, r , is provided to turn the worm-wheels simultaneously when the shaft p is revolved.

In Fig. 9 the nut and its worm-wheel are shown in detail. The nut is shaped to fit within the bearing o' in each end of the beam, and thereby hold the worm meshed in the teeth of the worm-wheel in the desired manner. A collar, n^2 , is shown formed upon the nut to hold the bearing o' contiguous to the hub of the worm-wheel in the required manner. To rotate the shaft p , a shaft, p' , is mounted in a bearing, p^2 , transverse to the beam, and is provided at one end with a pulley, q , while a pair of miter-wheels, r' , serve to connect the shafts p and p' and to rotate the shaft p when the pulley q is revolved.

The means for revolving the pulley is shown in Figs. 2 and 3, and consists in a grooved pulley, t , mounted upon the frame A, an endless cord, t' , carried therefrom to the pulley q , and a tightener to press the cord against the pulley t when required. The cord t' is carried horizontally along the front of the machine and over guide-pulleys t^2 upon the edge of the frame A, so as to permit a vertical movement of the pulley q without affecting the tension of the cord. To introduce the tightener between the pulley t and the pulleys t^2 , the pulley t is arranged upon a stud near the bottom of the frame A, and is driven by a belt, t^1 , from a grooved pulley secured to the clutch-pulley D.

The tightener consists in a lever, u , with arms carrying two pulleys, u' and u^2 , and is furnished with a weight, v , at its inner end to keep the lever normally raised and the cord slackened upon the pulley t . The cord is carried over one of the guide-pulleys, t^2 , which turn loosely, and thence passes beneath the pulley t and over and under the tightener-pulleys u' and u^2 , and then over the other guide-pulley, t^2 , back to the pulley q . The depression of the lever u overcomes the weight v and tightens the cord t' , so that the motion of the pulley t is transmitted to the pulley q and shaft p and worms r . When the cord t' is slack, it may readily be slipped from the pulley q by the operator and applied again to the pulley after giving it a half-turn—that is, applying that part of the cord to the top of pulley q which was before applied to the bottom. The effect of such change is to reverse the motion of the pulley q , as will be seen by reference to the arrows t^6 and t^7 , applied to the upper and lower parts of the cord, Fig. 2, and which show plainly that such parts move in opposite directions, and would necessarily rotate the pulley q in opposite direction when applied to the same side thereof. In Fig. 2

the arrow t^6 shows the cord moving to the left and applied to the top of the pulley q , which is consequently rotated in a direction opposite to the hands of a clock. The arrow t^7 shows the opposed part of the cord leading from the bottom of the pulley, moving to the right, and such part of the cord if applied to the top of the pulley would rotate it in the same direction as the hands of a clock. In short, the leading part of the cord on which the arrow t^6 is placed may be applied to the top or bottom of the pulley by the operator and determines the motion of the pulley in opposite directions. When the tightener is operated, the worms r turn the worm-wheels n' , and thus simultaneously shorten or lengthen the cross-head connecting-rods. On account of the great reduction in the arc of movement produced by the worm-wheels n' and the threads upon the connecting-screws $l l'$, one rotation of the pulley t produces a very minute change in the length of each connecting-rod, and the operator is thus able by a momentary depression of the tightening-lever u to produce a change of a single thousandth of an inch in the relations of the opposed dies. When the dies are properly adjusted, the slackening of the tightener loosens the cord t' and the worms and nuts n cease to move. To prevent any accidental shifting of the nuts, as by an unintentional pressure upon the lever u , jam-nuts n^3 are applied to the screws $l l'$ and may be tightened by the operator, if desired, to lock the nuts and screws in their adjusted position. Such jam-nuts are provided with holes to turn them by means of a rod, and would obviously require loosening before the nuts could be again adjusted by means of the tightener and cord t' . In practice no difficulty is found in reversing the relation of the cord t' to the pulley q , and an actuation of the nuts n in either direction is thus effected without complicating the mechanism.

In Fig. 1 the cross-head is shown depressed with the dies in contact, as in Fig. 4, while in Fig. 2 the cross-head is shown elevated with the dies separate to introduce the sheet metal for bending.

It will be obvious that the connection of the nuts n with the power-gearing actuated by the tightening-lever u enables the operator to shorten or lengthen the cross-head connections while the cross-head is in motion, and to thus adjust the die e to or from the die d with the sheet metal between them and without stopping the movements of the cross-head. A fresh die, e , may thus be secured to the cross-head and gradually adjusted toward the die d while in motion, or the pressure of the dies upon the sheet metal may be increased or diminished at pleasure without stopping the machine to effect the required adjustment of the dies.

I am aware that it is not new to use a connecting-rod with an expansion-nut in such presses to adjust the pressure of the dies, and

I do not, therefore, claim such nut as my invention.

To effect a mechanical connection with the mechanism vibrated, as before described, with the nuts, I employ the flexible cord t' and guide the same horizontally across the press, so that the end which is applied to the pulley q may be reciprocated and vibrated without affecting its tension.

10 It is obvious that the die d might be replaced by a grooved holder similar to d' , and changeable dies, either concave or convex, fitted in such groove like the die e .

Having thus set forth the nature of my invention, what I claim herein is—

15 1. In a double-crank press, the combination, with the crank-shaft and the cross-head, of two connecting-rods formed with right and left screws and expansion-nuts, as described, 20 worm-wheels affixed to the nuts, a nut-beam journaled upon the nuts adjacent to the worm-wheels, and a worm-shaft mounted upon the nut-beam with worms meshing in such wheels to rotate the nuts simultaneously, as and for 25 the purpose set forth.

2. In a double-crank press, the combination, with the crank-shaft and the cross-head, of two connecting-rods formed with right and left screws and expansion-nuts, as described, 30 worm-wheels affixed to the nuts, a nut-beam journaled upon the nuts adjacent to the worm-wheels, a worm-shaft mounted upon the nut-beam with worms meshing in such wheels, a pulley mounted upon the nut-beam to rotate such shaft, and a cord or belt applied to said 35 pulley, as and for the purpose set forth.

3. In a double-crank press, the combination, with the crank-shaft and the cross-head, of

two connecting-rods provided with expansion-nuts having worm-wheels secured thereon and 40 a nut-beam journaled upon the nuts adjacent to such wheels, a worm-shaft mounted upon the nut-beam, and worms meshing in such wheels, a pulley mounted upon the nut-beam near one end of the press to rotate the 45 worm-shaft, guide-pulleys mounted upon the frame near the other end of the press, a driving-pulley located upon the frame below said guide-wheels, and a tightener interposed between the driving-wheel and guide-wheels 50 and weighted to normally relax the cord, substantially as herein shown and described.

4. In a double-crank press, the combination, with the crank-shaft and the cross-head, of two connecting-rods formed with right and 55 left screws and expansion-nuts, as described, worm-wheels affixed to the nuts, a nut-beam journaled upon the nuts adjacent to the worm-wheels, a worm-shaft mounted upon the nut-beam with worms meshing in such wheels, a 60 pulley mounted upon the nut-beam to rotate such shaft, a driving-pulley, D , actuating the crank-shaft k' , the pulley t , rotated by means of cord t' from said pulley D , and cord t' , extended from pulley t to the pulley upon the 65 nut-beam, and a tightener applied to said cord, the whole arranged and operated substantially as set forth.

In testimony whereof I have hereunto set my hand in the presence of two subscribing 70 witnesses.

FRANK M. LEAVITT.
